Specification for Design.

Patented Mar. 9, 1920.

Application filed June 27, 1918. Serial No. 242,295. Term of patent 7 years.

To all whom it may concern:

Be it known that I, SCHUYLER BENJAMIN, a citizen of the United States, and a resident of Gloversville, Fulton county, State of New York, have invented a new, original and ornamental Design for Gloves, of which the following is a specification, reference being had to the accompanying drawing, forming part thereof.

The figure is a view, taken from the inside or palm side, of the fully extended glove.

I claim:

The ornamental design for a glove as shown.

In testimony whereof I have hereunto set my hand.

SCHUYLER BENJAMIN.
